UNITED STATES PATENT OFFICE.

EDMUND CORBIN, OF CHICAGO, ILLINOIS.

DRAWING IMPLEMENT.

1,381,971.

Specification of Letters Patent. Patented June 21, 1921.

Application filed June 4, 1920. Serial No. 386,637.

To all whom it may concern:

Be it known that I, EDMUND CORBIN, a citizen of the United States, residing at Chicago, in the county of Cook and State of Illinois, have invented new and useful Improvements in Drawing Implements, of which the following is a specification.

The device which is the subject matter of the present application for patent has been devised more particularly for facilitating the drawing of perspective views, the device enabling the draftsman to readily locate the vanishing point, and to draw all lines converging to this point without the use of an extra long ruler and a long table, where the vanishing point is located beyond the limits of the drawing board.

The device consists in a novel combination and arrangement of parts to be herein-after described and claimed, and in order that the same may be better understood, reference is had to the accompanying drawings forming a part of this specification.

In the drawings,

25 Figure 1 is a plan view of the implement; Fig. 2 is an edge view of a fragment thereof;

Fig. 3 is a cross section on the line 3—3 of Fig. 1;

30 Fig. 4 is a plan view showing a modified structural detail;

Fig. 5 is a plan view illustrating the manner in which the implement is used, and Fig. 6 is a perspective view showing a

35 different adjustment of the implement.

Referring specifically to the drawings, the device resembles a T-square, with the exception that the usual rigid head is absent and in its stead a resilient member to be presently described is employed. The straight edge or blade of the square is shown at 10, and it is provided with inch graduations.

To one end of the blade 10 is fastened, crosswise, a resilient strip 11 projecting equal distances from the graduated or working edge of the blade, and having its outer ends fitted with forks 12 which are offset rearwardly so that a bar 13 connected to the forks and extending therebetween lies spaced rearwardly from the strip 11, and parallel to said strip in the normal position of the latter, as shown in Fig. 1.

The bar 13 is rigid, and it is pivoted to one of the forks 12, as shown at 14, with the opposite end seating loosely between the branches of the other fork so that a cross

pin 15 carried by the latter may seat against the outer edge of the bar, said edge being toothed or serrated, as shown at 16, to permit a locking engagement between the pin 60 and the bar.

As the strip 11 is resilient it may be bowed more or less as shown in Figs. 5 and 6, this being made possible by the sliding connection of the bar 13 with the fork 12 65 carrying the pin 15, and the strip, in view of its inherent expansive tendency is held bowed by said pin when it is in engagement with the teeth 16. In its bowed position, the strip 11 describes an arc of a circle, with 70 the bar a chord of such circle, and in one position of the strip bar becomes the diameter of a circle. The strip can be flexed to describe an arc which is more or less than the semi-circumference of a circle, Fig. 5 75 showing it flexed to more than a semi-circumference, and Fig. 6 to less. The bar 13 is graduated to denote the radii of the various arcs the strip 11 may assume, and the strip is set to describe the desired arc by 80 bowing it until the pin 15 seats in a tooth 16 opposite the graduation denoting the radius of the desired arc.

The strip 11 may be rigidly attached to the blade 10, but a foldable connection as 85 shown in Figs. 1 and 3 is preferable. Here the blade end is shown recessed to seat a tongue or shank 17 extending from the strip, with a pivot pin 18 passing therethrough, and a stop pin 19 seating in an 90 edge recess 20 in the tongue.

Fig. 4 shows a separate connection between the blade 10 and the strip 11. Here, the strip has a tongue 21 as before, seating in an end recess in the blade, and said 95 tongue has a longitudinal slot 22 opening through its inner end, and seating pins 23 passing through the recessed end portion of the blade.

The manner in which the device is used 100 is illustrated in Figs. 5 and 6, in which the reference numeral 24 denotes an ordinary drawing board. Assuming now that the distance of the vanishing point 0 in Fig. 5, on the horizontal line A—B from the vertical line C—D has been ascertained by proper calculation, the operator measures the distance from the line C—D to the strip 11 along the line A—B, by means of the scale on the blade 10, after which the strip is bowed to a radius corresponding to 110 the difference between this measurement and

the distance between the line C—D and the point 0. The operator now drives two pins 25 into the face of the drawing board 24 in such position that they seat inside the arc 5 described by the strip 11 and in contact therewith. The blade 10 may now be used for drawing all lines which converge at the point 0, this being the vanishing point. The blade 10 can be set at various angles by sim- 10 ply allowing the bowed strip 11 to slide along the pins 25, this movement being in a circular path having the point 0 for its center.

The device is especially useful where the 15 vanishing point is beyond the limits of the drawing board 24, as shown at 0' in Fig. 5. The device is set and used as hereinbefore described, and it obviates the use of a long ruler and table. The device also requires 20 no extended mathematical calculation for locating the vanishing point, and it can be easily set to obtain the same.

The device can be used at either end of the drawing board, it being necessary only 25 to invert it if it is to be used at the end of the drawing board 24 opposite the end it is shown in the drawings. The same straight edge is now used, and it will be understood that both sides of the blade 10 will be grad- 30 uated.

I claim:

1. A drafting implement comprising a straight-edge blade, a resilient strip attached crosswise to one end thereof, and means for 35 adjusting said strip to assume an arcuate curve, said curved strip being adapted for sliding contact with a means for guiding it in a circular path having for its center the center of the arc to which the strip is curved.

2. A drafting implement comprising a 40 straight-edge blade, a resilient strip attached crosswise to one end thereof, means for adjusting said strip to assume an arcuate curve, and means associated with said adjusting means for indicating the radius of the curvature of the strip, said curved strip being 45 adapted for sliding contact with a means for guiding it in a circular path having for its center the center of the arc to which the strip is curved.

3. A drafting implement comprising a straight-edge blade, a strip attached cross- 50 wise to one end thereof, said strip being resilient for adjustment to assume an arcuate curve, and a rigid bar connected to one end 55 of the strip and having an adjustable connection with the other end for effecting said adjustment of the strip, said curved strip being adapted for sliding contact with a means for guiding it in a circular path hav- 60 ing for its center the center of the arc to which the strip is curved.

4. A drafting implement comprising a straight-edge blade, a strip attached cross- 65 wise to one end thereof, said strip being resilient for adjustment to assume an arcuate curve, and a rigid bar connected to one end 70 of the strip and having an adjustable connection with the other end for effecting said adjustment of the strip, said bar hav- 75 ing graduations to indicate the radius of the curvature of the strip, said curved strip being adapted for sliding contact with a means for guiding it in a circular path having for its center the center of the arc to which the strip is curved.

In testimony whereof I affix my signature.
EDMUND CORBIN.
